UNITED STATES PATENT OFFICE.

MAHLON E. LAYNE AND SAMUEL N. HALL, OF HOUSTON, TEXAS.

WRENCH.

No. 889,245.

Specification of Letters Patent.

Patented June 2, 1908.

Application filed December 3, 1907. Serial No. 404,935.

To all whom it may concern:

Be it known that we, MAHLON E. LAYNE and SAMUEL N. HALL, citizens of the United States, residing at Houston, in the county of Harris and State of Texas, have invented certain new and useful Improvements in Wrenches, of which the following is a specification:

The invention relates to wrenches and particularly to pipe wrenches of the chain type. The invention has for its objects; the provision of simplified and improved construction of the double acting type; the provision of a wrench in which both of the jaws employed are similar, and as a result interchangeable; and the provision of a wrench of inexpensive construction which is easily and effectively applied and operated. One embodiment of the invention is illustrated in the accompanying drawings, wherein:—

Figure 1 is a side elevation of the operative parts of the wrench, a portion of the handle and of the grip chain being broken away,

Figure 2 is a perspective view of the end of the handle,

Figure 3 is a side elevation of the inside face of one of the jaw-plates,

Figure 4 is a longitudinal section through the grip jaw on the line IV—IV of Figure 3, and

Figure 5 is an end view of the wrench.

The wrench is of the general type shown in our co-pending application Serial No. 404,934, but differs therefrom in that, the detachable engagement of the grip-chain is made with the end of the handle instead of with the jaw plates, and the handle is substantially straight at the end instead of being bent at an angle of 45° as in the co-pending application. Referring to the drawings, 1 is the handle having the operating end 2 as shown in detail in Figure 2. As here illustrated the end is enlarged and provided with the slot 3 for the reception of the chain, and the cross-blocks 4 provided at their upper ends with the hooks 5, for detachably engaging the chain. The chain is of the type ordinarily employed in devices of this kind, wherein the pintles 6 project past the side

plates 7, which construction adapts the chain to fit between the sides of the hooks 5, while the ends of the pintles project out laterally a sufficient distance to engage the front sides of such hooks. 8 are the jaw-plates, one of which is fitted to each side of the end of the

handle, and clamped in position by means of the transverse bolt 9 passing through such jaw-plates, and the cross-blocks 4. The outer sides of such blocks project above the surface of the end 2 and constitute tongues 60 for engagement with the jaw plates as hereinafter set forth. Each of the plates is provided at its opposite ends with the sets of teeth 10 whereby the device is made double acting, that is, the pipe engaged by the 65 wrench may be turned in both directions. The recess 11 is provided intermediate the sets of teeth 10 in order to permit of the transfer of the pipe from one set of teeth to the other without releasing the chain, and in 70 order to provide the slack in the chain for its release when the pipe is placed in such central recess 11. Each of the jaw-plates is provided with the transverse groove 12 for fitting over the projecting tongue portions of the 75 cross blocks 4, whereby the plates are held rigidly against turning, when the clamp bolt 9 is tightened. It will be noted that the jaw-plate is symmetrical on opposite sides of the center line A—A (Figure 3) which construction provides for the interchangeability of the jaws from one side of the handle to the other, so that the jaws on both sides are exactly alike and only one set of dies is necessary for the production of the jaw-plates. 80 The end of the grip chain is permanently secured in the slot 3 by means of a rod or rivet passing through the chain, and the openings 13 in the end of the handle. This rod or rivet may be either securely fixed in the 85 handle by means of heads or nuts, or may be of the same diameter throughout and in this case prevented from displacement by means of the jaw-plates which overlap the openings 13. It will be seen that by arranging the 90 permanent securing means upon the handle as well as the hooks 5, the construction of the jaw-plates 8 is simplified and cheapened and projecting parts on the jaw-plates are avoided which would render difficult the making 95 of such jaw-plates reversible and interchangeable.

Having thus described our invention and illustrated its use, what we claim as new and desire to secure by Letters Patent is the 105 following:—

1. In combination in a wrench, a handle having at the end means for detachably engaging a grip chain, a pair of similar and interchangeable jaw-plates secured to oppo- 110

site sides of the end of the handle and each provided with two sets of oppositely acting teeth on the same side of the jaw plate, and a grip chain secured to the end of the handle 5 on the side opposite to the other means for engaging the chain.

2. In combination in a wrench, a handle having hook engaging means at one side of its end, a pair of similar and interchangeable 10 jaw-plates secured to the opposite sides of the end of the handle and each provided with two sets of oppositely acting teeth on the same side of the jaw plate and a grip chain secured to the end of the handle on the side 15 opposite to the hook engaging means.

3. A wrench comprising a handle and a pair of jaws each provided with two sets of oppositely acting teeth on the same side of the jaw and fitting opposite sides of the end 20 thereof, the said handle and jaws having interfitting means symmetrically placed with respect to the transverse center line of the jaws whereby both jaws will fit either side 25 of the handle.

4. A wrench comprising a handle and a pair of interchangeable jaws each provided with two sets of oppositely acting teeth on the same side of the jaw toothed for double action and fitting opposite sides of the end 30 thereof, the jaws being at an angle to the handle and having a tongue and groove engagement transverse of the center of the jaws whereby both jaws will fit either side 35 of the handle.

5. In combination, a handle, a pair of interchangeable jaw-plate each provided with two sets of oppositely acting teeth on the same side of the jaw plate fitting on opposite sides of the end of the handle and having the 40 longitudinal axis at an acute angle to the axis of the handle, means for rigidly securing

the jaws to the handle and a grip chain for coöperating with the jaw-plates.

6. In combination, a handle, a pair of interchangeable jaw-plates each provided with 45 two sets of oppositely acting teeth on the same side of the jaw plate fitting on opposite sides of the end of the handle and having the longitudinal axis at an acute angle to the axis of the handle, means for rigidly securing 50 the jaw-plates to the handle and a grip chain fastened to one side of the end of the handle and adapted to be adjustably and detachably secured to the other side of the end of the handle. 55

7. The combination with a handle and a pair of interchangeable jaws each provided with two sets of oppositely acting teeth on the same side of the jaw for the opposite sides of the end thereof, of securing means 60 arranged at the transverse center line of the jaws and comprising co-acting grooves and tongues on the opposite parts so arranged that the jaws are interchangeable, and a co-operating grip chain. 65

8. In combination, a handle having a slotted end, a pair of interchangeable jaws each provided with two sets of oppositely acting teeth on the same side of the jaw arranged one on either side of the end of the handle and at an acute angle thereto, and a grip chain having one end secured in the slot and adapted to form a loop and be secured adjustably to the end of the handle. 70

In testimony whereof we have hereunto 75 signed our names in the presence of the two subscribing witnesses.

MAHLON E. LAYNE.
SAMUEL N. HALL.
